Primary Examiner — Kevin K Rudzinski*Assistant Examiner* — Clare Ann Gannon(57) **CLAIM**

The ornamental design for the garment supporter, as shown and described.

DESCRIPTION

FIG. 1 is a top perspective view of a garment supporter showing my new design, in accordance to its flattened, buckled configuration;

FIG. 2 is a bottom perspective view thereof;

FIG. 3 is a rear perspective view thereof;

FIG. 4 is a front elevational view thereof;

FIG. 5 is a rear elevational view thereof;

FIG. 6 is a left elevational view thereof;

FIG. 7 is a right elevational view thereof;

FIG. 8 is a top plan view thereof, the bottom plan view being mirrored thereto;

FIG. 9 is a front perspective view thereof, shown in a released configuration;

FIG. 10 is an enlarged detail view thereof, depicting area 10 in FIG. 1;

FIG. 11 is an enlarged detail view thereof, depicting area 11 in FIG. 6;

FIG. 12 is an enlarged detail view thereof, depicting area 12 in FIG. 7;

FIG. 13 is an enlarged detail view thereof, depicting area 14 in FIG. 8; and,

FIG. 14 is an enlarged detail view thereof, depicting area 14 in FIG. 10.
